VEHICLE SIGNAL

Clifton Sprouse, Abbeville, S. C.

Application August 10, 1935, Serial No. 35,663

20 Claims. (Cl. 177—337)

This invention relates to the class of signalling and pertains particularly to signal mechanism for use upon wheeled vehicles, particularly automobiles.

5 The primary object of the present invention is to provide a novel motor vehicle signal in which a composite symbol is employed with means for exposing different portions of the same whereby the giving of information regarding the intentions of the driver of the vehicle upon which the signal is mounted, is accomplished.

Another object of the invention is to provide in a motor vehicle signal of the above described 10 character, a novel means for exposing the desired portions of the composite symbol to effect the giving of a desired signal.

Another object of the invention is to provide 15 a novel motor vehicle signal in which each of the several signals is set by hand but has means associated therewith whereby the shutting off of the signal is accomplished automatically by the normal manipulation of certain parts of the motor vehicle control mechanism.

A still further object of the invention is to provide 20 a novel means in association with a signal of the character set forth, wherein the setting of one signal effects the shifting of a control element by which the subsequent manipulation of another signal setting element is prevented until the first signal is shut off.

The invention will be best understood from a consideration of the following detailed description taken in connection with the accompanying drawings forming part of this specification, with 25 the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view illustrating the several parts 30 of the signalling mechanism embodying the present invention, showing the same more or less diagrammatically;

Figure 2 is a view in elevation of the face or front of the signal box;

Figure 3 is a vertical central section through 35 the signal box;

Figure 4 is a view in rear elevation of the signal box with the rear side removed and showing the electrical circuit associated therewith;

Figure 5 is a sectional view taken substantially 40 upon the line 5—5 of Figure 1.

Referring now more particularly to the drawings, the numeral 1 indicates generally the signal housing comprising part of the present signalling mechanism, the front side or face of which is indicated by the numeral 2, which face is directed rearwardly of the motor vehicle upon which the signal housing is mounted. This housing is designed to be placed in any suitable position upon a motor vehicle where the face 2 may be readily seen by drivers of following cars. The 10 opposite or rear face of the housing is closed by the wall 3 and the front and rear walls, together with the surrounding side wall 4, are secured to a frame 5, the upper end of which is pointed, as illustrated in Figures 1 and 4, and which has a 15 cross bar 6 in its upper part upon which certain elements of the signal housing are mounted.

5 The front wall 2 has a composite symbol aperture 7 therein which is substantially in the form of a fleur-de-lis, thus providing a lower vertically extending opening which merges at its upper end into the laterally curving points 8 and the longitudinally continuing point 9. Directly above the point 9, the wall 2 of the housing has a window opening 10 in which is a lens or transparent 20 panel 11 which is colored red.

The front wall 2 has a composite symbol aperture 7 therein which is substantially in the form of a fleur-de-lis, thus providing a lower vertically extending opening which merges at its upper end into the laterally curving points 8 and the longitudinally continuing point 9. Directly above the point 9, the wall 2 of the housing has a window opening 10 in which is a lens or transparent 25 panel 11 which is colored red.

Within the housing frame 5, a glass panel 12 is disposed vertically, lying in a plane between the front wall 2 and the bar 6 and extending downwardly from the bar to the bottom of the 30 frame. This bar 6 carries adjacent each end a pivot pin 13 and upon each pivot pin 13 is oscillatably mounted an actuator plate one of which is designated 14R and the other 14L, and each of which has a downwardly extending tail portion 15 which is normally directed inwardly toward the vertical center of the housing and which has its inner side concavely curved to form a camming surface 16. At the upper end of each plate is an upwardly and inwardly curving horn 17 40 which, like the tail 15 of the plate, lies between the longitudinal center of the housing and the pivot on which the actuator plate is mounted. These horns 17 are in upwardly converging relation as shown while the tails 15 are in downwardly directed convergent relation.

Lying outwardly of the pivot 13 of each actuator plate with respect to the longitudinal center of the housing is a finger 18 forming a part of the plate to which an end of an actuating Bowden 50 wire 19 is attached.

Each of the actuator plates 14R and 14L has a portion projecting over the top edge of the plate 12, as indicated at 19 in Figure 3, and to this projecting portion is secured a shield or cover wing 55

20 which is of opaque material and which normally covers a portion of the composite symbol opening 7, as is clearly illustrated in Figure 1. Each of these wings 20 has an arcuate edge 21 which is remote from the other wing and which, when the wing is swung to a predetermined position, conforms with an edge of the symbol opening to cause a desired signal symbol to be formed by the exposure of a portion of this opening. As illustrated in Figure 2, the wings 20, together with their actuating plates 14R and 14L, are swung to a position where the lower portion of the composite symbol opening is uncovered together with one laterally directed arrow portion 8 so as to form a complete direction indicating arrow. The wings 20 coact to cover up the remaining part of the symbol opening so that only the desired arrow form stands out.

Secured to the frame of the signal housing are 20 two relatively long leaf springs, each of which is indicated by the numeral 22. Each of these springs is attached against movement at one end to the housing frame while the other end is slidably joined with the tail portion 15 of the adjacent actuator plate by two guide elements 23 or by any other suitable means. These springs normally tend to swing the free ends of the tail portions 15 together and toward the vertical center of the signal housing so as to maintain the wings 30 20 in overlapping relation when the signal element is inoperative. Slidably mounted in the top of the housing frame is a plate 24 which has vertical movement and which has the flange 25 at its lower edge which overlies and is normally free 35 of contact with the horns 17 of the actuator plates, as illustrated in Figure 1. This flange 25 has one end of a Bowden wire 26 connected therewith and when this wire is moved in the proper direction to draw the plate 24 downwardly, the 40 flange 25 will simultaneously contact the horns of the two actuator plates so as to cause the latter to be oscillated in a direction to move the tail portions 15 apart against the resilient action of the springs 22. This will likewise move the wings 45 20 from the overlapped relation in which they are shown in Figure 1 so as to uncover only the central part of the composite symbol opening 7 and thus expose a straight arrow directed vertically of the signal housing. When the wings are moved 50 to this relation or when they are moved in the proper manner to form an arrow directed to the right or to the left, the translucent plate 12 will be exposed through the uncovered portion of the symbol opening. Also when the wings 20 are os- 55 cillated in the proper manner to uncover a portion of the symbol opening to form a right or left turn indicating arrow, a portion of one wing will move into position across the window 11 so as to prevent light developed by suitable illuminating means, as hereinafter described, from passing from the interior of the housing through this window. When the wings are swung apart through the actuation of the plate 24 in the manner described, they will not cover the window 11 60 so that the light referred to will illuminate the window as well as the signalling symbol formed.

At any suitable point adjacent the operator of the vehicle upon which the signal is mounted, three actuating buttons 27, 28 and 29 are mounted for reciprocatory movement, each button having a shaft 30 terminating in a head 31. Each of two of the buttons is connected by a Bowden wire 18' with the finger 18 of one of the actuator plates 14R and 14L. These buttons are marked 75 "R" and "L" for the right and left turn signals.

The third button, which is marked "S" is connected by the Bowden wire 26 with the plate 24 and when actuated gives the stop signal. Each of these signal buttons has a pin 32 carried by its shaft 30 which engages in a slot 33 formed in a plate 34 which is mounted for movement transversely of the shafts 30. These slots are substantially in the form of a figure 7, each having a short transverse end portion which at one end emerges into an obliquely directed portion and this in turn flows into a straight portion which is perpendicular to the said end portion, as illustrated in Figure 1. The pin 32 adjacent each slot normally positions in the same at the point of joinder of the transverse portion of the slot with the oblique portion, so that when any one of the shafts 30 is shifted in one direction the pin thereof will cam against the edge of the oblique portion of the adjacent slot to shift the plate 34 transversely of the shaft and the pin will then 20 pass into the long straight portion of the slot. The pins of the other shafts will, however, become located in the opposite end of the transverse portion of the slot with which each is associated so that the shafts thereof cannot be moved. By this 25 means, when one signal actuating button is pulled by the operator of the signal, the other buttons will be locked against movement.

Each of the right and left turn signal button shafts has its head portion 31 connected by a rigid 30 wire or rod 34 with one end of a lever bar 35, and the central portion of this lever bar is connected by a Bowden wire 36 with an oscillatably mounted cam plate 37 which has the two oppositely directed camming surfaces 38 and an arm 39 to 35 which the Bowden wire 36 is connected. This cam plate 37 is mounted in a suitable position adjacent the steering shaft 40 of the motor vehicle where a pin 41 carried by the steering shaft or by mechanism directly connected therewith for operation thereby, will move across the point connecting the cam surfaces 38 during the oscillation of the steering shaft 40. This pin 41 extends at one end through the shaft, as shown in Figure 1, the end of the pin being flush with the 45 top of the shaft and extending downwardly therefrom on the underside thereof. By this mechanism when either the right or left turn signal is set or established manually, it will be dis-established automatically as will be readily apparent from the following. If the right turn signal is to be established, the operator pulls back upon the button 27 so as to draw the Bowden wire 18' which is attached thereto and thus effect the os- 50 cillation of the actuator plate 14R in Figure 1. This will swing the associated wing member 20 across the other wing member and uncover the adjacent arrow point 8 and the lower end of the opening 7 in the manner illustrated in Figure 2 60 and at the same time cover the window 11. Also at the same time, the wire or rod 34 which is connected with the button 27 will be pulled back causing the bar 35 to fulcrum at its opposite end upon the other wire 34 and pull upon the Bowden 65 wire 36 to oscillate the cam plate 37 and bring one of the surfaces thereof into position across the steering shaft or column. As the steering operation takes place to make the turn, the pin will contact the cam surface 38 nearest thereto and 70 swing the plate back to the normal position in which it is shown in Figure 1 and thus pull the button shaft 27 back to its original position and at the same time force the Bowden wire 18' which is attached thereto back so as to return the actu- 75

ator plate and the wing with which it is connected to their normal positions.

The numeral 42 indicates a reciprocable bar which is attached in any suitable manner, as by the link 43, with the brake pedal of the vehicle. The forward end of this bar 42 carries a transverse pin 44 and has a longitudinal slot 45 therein. Supported in any suitable manner to extend through the slot 45, and held against movement, is a guide pin 46 which supports the bar 42 in its reciprocatory motion and mounted for oscillation on this pin is a plate 47 to which is attached one end of a rigid wire 48, the other end of which is attached to the shaft 30 of the stop button 28. Disposed between the forward end of the bar 42 and the plate 47 is a latch plate 49 which has a slot 50 therein through which the pin 46 passes and through which the stem of a button 51 passes, which stem is engaged in and carried by the plate 47. The latch plate 49 is thus permitted longitudinal movement relative to the plate 47 but is caused to oscillate with this plate when the wire 48 is pulled. The latch plate 49 also carries a pin 52 adjacent its upper end which extends laterally across the downturned end of an arm 53 which is pivotally mounted at 54. The pin 52 is above the upper end of the slot 50. Also pivotally mounted upon the pin 54 is a weighted plate 55 which has a rear extension carrying a weight 56 and beneath which extension a lateral flange 57 at the rear end of the arm 53 engages. At the end extending forwardly of the pivot 54, the counterbalanced plate 55 has a forwardly and downwardly curving finger 58 which is in the path of the rear edge of the latch plate 49 when the latter is oscillated with the plate 47.

With this construction, when the stop button 28 is pulled to swing the wings 20 apart so as to uncover the central part of the symbol opening and to uncover the window 11, the wire 48 will be pulled to swing the plates 47 and 49 to upright position. The rear edge of the plate 49 will press against the rounded finger 58 so as to raise the weight 56 and allow the forward end of the bar 53 to drop. Consequently, as the plate 49 moves to vertical position, it will also drop onto the pin 44, and as the brake pedal is depressed in stopping the machine, the bar 42 will move forwardly so as to shift the pin 44 to a position beyond the forward edge of the latch plate 49, thus allowing the latch plate to drop further, to bring its lower edge below the pin 44. When the brake pedal is released and the spring controlling the same pulls it back into inoperative position, the bar 42 will also be retracted, causing the pin 44 to hit the lower front edge of the latch plate 49 and cause it to be oscillated to the position in which it is shown in Figure 5 and at the same time cause the plate 47 to oscillate to the same position. This will pull the wire 48 and thus restore the stop signal to its non-signalling position through the return of the stop button shaft 30 to its initial position.

In Figure 4 there is illustrated an electrical diagram by which the illumination of the interior of the housing and the lighting of tell-tale lights is effected upon the manipulation of the buttons 27, 28 and 29.

The numeral 59 indicates a battery or other suitable source of electrical current. From one side of this current source a current return lead wire 60 connects with one side of the series of pairs of switch points which are indicated by the numerals 61, 62, 63, 64, and 65.

The numerals 27', 28' and 29' indicate, respectively, tell-tale lights for the buttons 27, 28 and 29, and these are connected on one side with the current carrying wire 66 and at their opposite sides, respectively, with the opposite sides 5 of the pairs of switch points 61, 62 and 63.

The current carrying wire 66 has in circuit therein the lamp 67 which is disposed in the center of the housing between the actuator plates 14R and 14L and this wire is connected with the 10 opposite sides of the pairs of switches 64 and 65.

When the right turn signal button 27 is operated to actuate the plate 14R, the metallic bridging element 68 which is carried by this plate connects the terminals of the switch 61 so as to 15 close the circuit in which the tell-tale lamp 27' is located. At the same time, the free end of the tail portion 15 of the plate 14R rides onto the arcuate edge of the tail of the opposite plate 14L and causes this plate to bring the metallic 20 bar 69 into bridging relation between the terminals of the switch 65, thus closing the circuit which lights the housing illuminating lamp 67.

When the left turn signal button 29 is actuated, the actuator plate 14L will be oscillated so that 25 the free end of the tail portion 15 thereof will ride against the curved inner edge of the tail portion of the opposite plate 14R, at the same time bringing the metallic bar 69 into bridging relation between the terminals of the switch 64 30 to effect the illumination of the lamp 67 and bringing the second metallic bar 70 which is carried upon this plate 14L into bridging relation between the terminals of the switch 63 which lights the tell-tale lamp 29'. 35

When the stop signal button 28 is actuated to pull down the plate 24 and cause the simultaneous oscillation of the two plates 14R and 14L by which their lower or tail ends are swung apart, the metallic bridging element 71 carried by the 40 plate 24 electrically connects the terminals of the switch 62 to light up the tell-tale lamp 28'. With this operation, the switch 65 is closed by the bar 69 so as to illuminate the housing lamp 67.

It will be noted upon reference to Figure 1 45 that both of the wing members 20 lie with a portion covering the central part of the opening 7. Thus it will be observed the movement of only one wing member would not effect the formation of the proper indicating arrow for a right turn, 50 left turn or stop signal, therefore, when a right turn or left turn signal is to be given the actuator plate which is primarily moved not only effects the uncovering of the proper arrow point and the lower part of the opening 7, but also 55 effects the necessary movement of the other actuator plate and wing to completely expose the lower part of the signal opening to the passage of illuminating light rays from the lamp 67.

From the foregoing, it will be readily apparent 60 that by means of the signal mechanism herein described, a clear and distinctive right or left turn or stop signal may be given and that novel means is employed for restoring the movable parts to normal position after the necessity for the giving of a signal is past.

What is claimed is:—

1. A motor vehicle signal, comprising a casing having a wall provided with a composite signal symbol opening having distinctive outline portions, one of which portions is common to the other portions and is designed to coat with a selected one of the said other portions to form a signal, movable means within the casing normally covering said opening and adapted for move- 70 75

ment relative to the opening to effect the uncovering of one of said selected portions with said one portion whereby a right turn, left turn or stop symbol may be formed, and means for effecting shifting of said movable opening covering means.

2. A motor vehicle signal, comprising a casing having a wall provided with a composite signal symbol opening having distinctive outline portions, one of which portions is common to the other portions and is designed to coact with a selected one of the said other portions to form a signal, movable means within the casing normally covering said opening and adapted for movement relative to the opening to effect the uncovering of one of said selected portions with said one portion whereby a right turn, left turn or stop symbol may be formed, means for effecting shifting of said movable opening covering means, an auxiliary signalling means comprising a window opening in said wall, and means whereby the auxiliary signalling means is made operative only upon the formation of the said stop symbol.

25 3. A vehicle signal, comprising a housing having a wall provided with a composite signal symbol opening having distinctive outline portions, one of which portions is common to the other portions and is designed to coact with a selected one of the said other portions to form a signal, a pair of wing members oscillatably mounted in the housing and normally coacting to cover said opening, and means for effecting the selective oscillation of said wing members for the uncovering of the said one portion and a selected one of the said other portions of said symbol opening to effect the formation of a desired indicating symbol.

4. A vehicle signal, comprising a housing having a wall provided with a composite signal symbol opening having distinctive outline portions, one of which portions is common to the other portions and is designed to coact with a selected one of the said other portions to form a signal, a pair of wing members oscillatably mounted in the housing and normally coacting to cover said opening, means for effecting the selective oscillation of said wing members for the uncovering of the said one portion and a selected one of the said other portions of said symbol opening to effect the formation of a desired direction indicating symbol, and each of said wing members having an edge formation designed to coact with a portion of the symbol opening in the formation of the desired signalling symbol.

5. A vehicle signal, comprising a housing having a wall provided with a composite signal symbol opening having distinctive outline portions, one of which portions is common to the other portions, and is designed to coact with a selected one of the said other portions to form a signal, a pair of wing members oscillatably mounted in the housing and normally coacting to cover said opening, means for effecting the selective oscillation of said wing members for the uncovering of the said one portion and a selected one of the said other portions of said symbol opening to effect the formation of a desired direction indicating symbol, an auxiliary signal comprising a window in the said casing wall, means for effecting the illumination of the interior of the casing upon the formation of either of two signal symbols, and means for effecting the illumination of said window upon the formation of a third sig-

nal symbol while maintaining the said two symbols unilluminated.

6. A vehicle signal, comprising a housing having a wall provided with a composite signal symbol opening, having a lower portion merging into two opposite laterally directed portions, a pair of oscillatably mounted wing members within the casing coacting to cover said opening, means for selectively oscillating said wing members for the selective uncovering of the laterally directed portions of said opening and the lower portion whereby either of a pair of oppositely directed curved arrows may be formed, and each of said wing members having a portion of one edge formed to coincide with an edge configuration of a portion of said opening to complete the formation of one of the said oppositely directed arrows.

7. A motor vehicle signal, comprising a housing having a wall provided with a composite signal symbol opening having a straight lower portion merging at one end into opposite laterally directed openings and a continuing terminal opening, a pair of wing members oscillatably mounted in the housing and each normally covering the central portion of said composite opening and one of the lateral extensions thereof, means for effecting the selective oscillation of said wings, each wing when oscillated by said means moving across the opposite lateral extension of the opening to uncover the lateral extension adjacent thereto and a portion of the straight portion of the opening whereby to form a curved direction indicating opening, and means for effecting the simultaneous oscillation in opposite directions of said wing members to uncover only the straight portion of said symbol opening and the said terminal continuation thereof for the formation of a straight direction indicating symbol.

8. A motor vehicle signal, comprising a housing having a wall provided with a composite signal symbol opening having a straight lower portion merging at one end into opposite laterally directed openings and a continuing terminal opening, a pair of wing members oscillatably mounted in the housing and each normally covering the central portion of said composite opening and one of the lateral extensions thereof, means for effecting the selective oscillation of said wings, each wing when oscillated by said means moving across the opposite lateral extension of the opening to uncover the lateral extension adjacent thereto and a portion of the straight portion of the opening whereby to form a curved direction indicating opening, means for effecting the simultaneous oscillation in opposite directions of said wing members to uncover only the straight portion of said symbol opening and the said terminal continuation thereof for the formation of a straight direction indicating symbol, a signalling window formed in said housing wall, and means for making said signal window operative as a signalling medium only upon the formation of the said straight signalling symbol.

9. A vehicle signal, comprising a housing having a wall provided with a composite signal symbol opening having a straight main portion merging at one end in oppositely directed lateral extensions and a continuing straight extension, said wall further having a signal window adjacent the end of the said continuing straight extension, a pair of wing members oscillatably mounted in the housing and normally coacting to cover the composite symbol opening, means for selectively oscillating the wing members to

uncover the main portion of said opening and a selected lateral extension whereby to form a continuous curved signalling symbol, a pair of elements coupled with said wings for movement therewith, a sliding plate adapted when moved in one direction to engage said elements, and means for effecting the movement of said plate into engagement with said elements whereby said wing members may be simultaneously oscillated for separation to uncover the central portion of said symbol opening and the terminal continuation thereof, each of said wing members when selectively actuated moving across and covering said window.

10 10. A vehicle signal, comprising a housing having a wall provided with a composite signal symbol opening having a straight main portion merging at one end in oppositely directed lateral extensions and a continuing straight extension, a pair of wing members oscillatably mounted in the housing and normally coacting to cover the composite symbol opening, means for selectively oscillating the wing members to uncover the main portion of said opening and a selected lateral extension whereby to form a continuous curved signalling symbol, a pair of elements coupled with said wings for movement therewith, a sliding plate adapted when moved in one direction to engage said elements, and means 20 for effecting the movement of said plate into engagement with said elements whereby said wing members may be simultaneously oscillated for separation to uncover the central portion of said symbol opening and the terminal continuation thereof.

25 11. A motor vehicle signal, comprising a housing having a wall provided with signalling opens defining a lower portion and three diverging upper portions, a pair of wing members oscillatably mounted in the housing, means for selectively manually oscillating said wing members for the selective covering or uncovering of said diverging portions with said lower portion whereby a right turn, left turn or stop signal may be established, means operated by and upon the actuation of the vehicle steering mechanism for disestablishing a selected turn indicating signal after the same has been established, and means actuated by the brake mechanism of the vehicle for disestablishing the stop signal after the same has been established.

30 12. A motor vehicle signal, comprising a housing having a wall provided with a composite signal symbol opening defined by three diverging upper portions and a lower portion common thereto, a pair of wing members oscillatably mounted in the housing and coacting to cover said opening, a pair of actuator plates oscillatably mounted in the housing and each coupled with a wing member, each of said plates having a lateral extension at one side of the pivot point thereof and an upwardly and inwardly curving horn at the opposite side of the pivot point, the said horns of the actuator plates being in convergent relation, a Bowden wire connection with the lateral extension of each actuator plate whereby the selective oscillation of the plates and wings may be effected, each of said wings when oscillated in one direction uncovering one of said diverging portions and the lower portion to give a turn signal, a reciprocable member in the housing adapted when moved in one direction to simultaneously contact said horns and effect the separatory swinging of the wing members to uncover one of said diverging portions

and the lower portion for the formation of a stop signal, an actuating Bowden wire connected with said reciprocable member, and means for effecting the selective actuation of the Bowden wires at a point remote from the signal.

5

13. A motor vehicle signal, comprising a housing having a wall provided with a composite signal symbol opening defined by three diverging upper portions and a lower portion common thereto, a pair of wing members oscillatably mounted in the housing and coacting to cover said opening, a pair of actuator plates oscillatably mounted in the housing and each coupled with a wing member, each of said plates having a lateral extension at one side of the pivot point thereof and an upwardly and inwardly curving horn at the opposite side of the pivot point, the said horns of the actuator plates being in convergent relation, a Bowden wire connection with the lateral extension of each actuator plate whereby the selective oscillation of the plates and wings may be effected, each of said wings when oscillated in one direction uncovering one of said diverging portions and the lower portion to give a turn signal, a reciprocable member in the housing adapted when moved in one direction to simultaneously contact said horns and effect the separatory swinging of the wing members to uncover one of said diverging portions and the lower portion for the formation of a stop signal, a Bowden wire connected with said reciprocable member, means for effecting the selective actuation of the Bowden wires at a point remote from the signal, and means whereby the actuation of one Bowden wire actuating means will secure against movement the means for actuating the other Bowden wires.

14. In a signal mechanism for a motor vehicle having an oscillatable steering shaft and a reciprocable brake actuator, a signal device comprising means for establishing a right turn, left turn or stop signal, manually actuated means for effecting the establishment of said signals, an oscillatable cam element which is shifted to a predetermined position upon the establishment of a right or left turn signal, means connected with said steering mechanism for engaging said cam to disestablish the right or left turn signal by the actuation of the steering mechanism after the selected signal is established, an oscillatable latch element which is shifted to a predetermined position upon the establishment of the stop signal, and reciprocating means actuated by the vehicle brake mechanism to disestablish the stop signal upon the release of the brake.

15. In a signal, a casing, a wall for the casing having a signal opening defining a lower portion and upwardly directed diverging portions, a pair of members pivotally mounted in the casing for relative oscillation and normally together completely covering said opening, and means for effecting the relative oscillation of said members whereby said lower portion and a selected diverging portion of said opening may be simultaneously uncovered to form together a desired signal.

16. In a signal, a casing, a wall for the casing having a signal opening defining a lower portion and upwardly directed diverging portions, a pair of members pivotally mounted in the casing for relative oscillation and normally together completely covering said opening, means for effecting the relative oscillation of said members whereby said lower portion and a selected

75

- diverging portion of said opening may be simultaneously uncovered to form together a desired signal, said members moving apart in forming one signal, and means forming parts of the members whereby the oscillation of one member in one direction will effect oscillation of the other member in the same direction for the formation of another signal.
17. In a signal, a casing, a wall for the casing having a signal opening defining a central lower portion and upwardly directed diverging portions, a pair of members pivotally mounted in the casing for relative oscillation and normally together completely covering said opening, means for selectively oscillating said members to uncover a selected divergent portion of the opening, said members when in the said opening covering position overlapping and each completely covering the said central lower portion of the opening below the diverging portions thereof, and means carried by each member which when a selected member is oscillated will engage the means of the other member to effect its oscillation sufficiently to uncover the said lower portion of the opening.
18. In a signal, a casing, a wall for the casing having a signal opening defining a lower portion and three upwardly directed relatively divergent portions, a pair of plate members pivotally mounted in the casing and normally acting together to cover said opening, said plate members being in overlapping relation, means for selectively oscillating said plate members, each member when oscillated swinging across the other member to uncover the lower portion of said opening, and an outside one of the said three portions, means carried by each member for effecting the partial swinging of the other member when a selected member is oscillated, a pair of contact fingers each carried by a plate member, and a reciprocable element adapted when moved 40 in one direction to engage said fingers to effect

the simultaneous swinging apart of the plate members and the uncovering of only the lower portion and the central one of the said three upper portions.

19. In a signal for a vehicle having a brake pedal, a casing having a stop signal opening, shiftable means normally covering the opening, manual means for shifting said shiftable means to display said signal, a reciprocably mounted element, means by which said element 10 may be coupled with said pedal for actuation thereby, a trip device which is set by and upon the operation of the said manual means, and means effecting the coupling of said reciprocable element with said trip device to restore the signal to non-signalling position upon restoration of said pedal to inoperative position.

20. In a signal including a casing having a signal opening and a plurality of shiftable elements in the casing for uncovering selected portions of the opening, an operating wire connected with each of said elements in the casing, a manually actuated reciprocable element connected with each of said wires, and means for maintaining the remaining ones of said reciprocable members against movement after one thereof has been shifted, comprising a plate member mounted for limited movement transversely of the reciprocable members and having a plurality of slots therein, each having a portion parallel 25 extending transversely thereof with a connecting oblique portion between the parallel and transverse portions, and a pin carried by each reciprocable member and engaging in the adjacent slot which cams in the said oblique portion of the slot when the reciprocable member is shifted to effect the shifting of the plate and the movement of the pins of the other members into the transverse slots.

CLIFTON SPROUSE. 40
